US00D898706S

(12) **United States Design Patent** (10) Patent No.: **US D898,706 S**
(45) Date of Patent: **** Oct. 13, 2020**

(54) **WIRELESS REMOTE-CONTROLLER**

(71) Applicant: **Wei Jiang**, Guangdong (CN)

(72) Inventor: **Wei Jiang**, Guangdong (CN)

(**) Term: **15 Years**

(21) Appl. No.: **29/692,533**

(22) Filed: **May 27, 2019**

(30) **Foreign Application Priority Data**

May 15, 2019 (CN) 2019 3 0235465

(51) LOC (12) Cl. **14-03**

(52) U.S. Cl.

USPC **D14/218**

(58) **Field of Classification Search**

Primary Examiner — John Windmuller

(57) **CLAIM**

I claim the ornamental design for the wireless remote-controller, as shown and described.

DESCRIPTION

FIG. 1 is a perspective view of a wireless remote-controller showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
